Horace W. Robbins of Baltimore Md.
Filed Patent No. 680 Nov. 28. 1854

The exclusive right to in this Letters Patent and making part of the name.

To all whom it may concern.

Be it known, That I, Horace W. Robbins of Baltimore City,
in the County of Baltimore and State of Maryland have invented and made a certain new
design for stoves and I do hereby declare, that the accompanying drawing fig. 1 is a correct delineation
of the same.

Having shown the formation of my design for a stove, which design I have
